(57) **CLAIM**

The ornamental design for a snack food product, as shown and described.

DESCRIPTION

FIG. 1 is a front and right side perspective view of a snack food product showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top end view thereof; and,

FIG. 7 is a bottom end view thereof.

The broken lines in FIGS. 1, 2 and 4-7 illustrate portions of the snack food product which form no part of the claimed design.

1 Claim, 4 Drawing Sheets
